SELF-ORIENTING RADIO DIRECTION
FINDER

Donald S. Bond, Philadelphia, Pa., and Wendell L. Carlson, Haddonfield, N. J., assignors to Radio Corporation of America, a corporation of Delaware

Application March 19, 1938, Serial No. 196,817

15 Claims. (Cl. 250—11)

Our invention relates to self-orienting radio direction finders, and particularly to a self-orienting direction finder in which the torque of the motor orienting the directive antenna is increased in the region adjacent the null point.

It has been proposed to couple a directive antenna to a motor whereby the directive antenna may be rotated until zero signal is induced in the antenna. At this position relay contacts or the like disengage the motor. Such systems are not entirely satisfactory because relay contacts are not always certain of operation. We propose to use a two-phase motor and adjust its movements by applying a current of fixed phase to one of the field windings of the motor and a current of reversible phase, which depends upon the orientation of the directive antenna, to the other field winding. When thus arranged, the two-phase motor will drive the directive antenna until a point of minimum or zero signal is reached. At this point, only the reference phase current is applied to the rotor, hence no rotation of the rotor takes place. We have found that a low motor torque, in the region near the point of null signal in the directive antenna, makes it difficult to operate a self-orienting antenna by means of an ordinary arrangement of radio receiver and two-phase motor.

One of the objects of our invention is to provide means for operating a self-orienting directive antenna by means of a two-phase motor. Another object is to provide means in a self-orienting direction finder whereby the motor torque is increased in the region near the minimum signal response. A further object is to provide means in a self-orienting direction finder whereby automatic sensitivity control is used to maintain the receiver output substantially constant.

In describing the invention, reference will be made to—

Figure 1, which is a circuit diagram illustrating one embodiment of our invention;

Figures 2 and 3 are response curves which illustrate the theory of operation; and

Figure 4 is a block diagram illustrating a modification of the invention.

Referring to Fig. 1, a shielded rotatable loop or any rotatable directive antenna is connected to the input of a radio frequency amplifier 3 by means of a radio frequency transformer 5. The output circuit 6 of the radio frequency amplifier includes elements which are adjusted to offer either an inductive or a capacitive reactance which advances or retards the phase of the cur-

rents substantially 90°. The output 8 of the radio frequency amplifier is connected to a pair of balanced modulators 7, 9. The output circuit of the balanced modulators is coupled by a primary winding 11 to a radio frequency transformer 13. Antenna 15 is also coupled by a primary winding 17 to the secondary of the radio frequency transformer. The secondary of the radio frequency transformer is connected to a radio receiving device 19. The radio receiving device may include a radio frequency amplifier, a detector, a local oscillator, an intermediate frequency amplifier, a second detector, an automatic sensitivity control, and an output circuit, which may include an audio frequency amplifier.

The output of the audio amplifier is connected to a thermionic amplifier 21. The output circuit of the thermionic amplifier is connected to a band pass filter 23 which, in turn, is connected to an audio amplifier tube 25. The output of the audio amplifier is applied to a pair of tubes 27, 29 which are connected in push-pull relation to an audio frequency transformer 31. The secondary of the audio frequency transformer is connected to one field winding 33 of a two-phase motor 35. The other field winding 37 of the motor is connected through a phase shifter 39 to an alternating current source which may be a generator 41 or the like. The generator is connected to a transformer 43. The secondary 45 of this transformer is connected in push-pull relation to the balanced modulator tubes 7, 9 by series impedances 46.

A connection 47 is made from the audio amplifier circuit 25 to the anode 49 of a diode rectifier which may be a part of the radio frequency amplifier 3 or a separate rectifier. The anode is also connected to ground by resistors 51. A connection is made from a point intermediate the ends of the resistors 51, through a filter 53, to the lower end of the secondary of the radio frequency transformer 5, which is connected to the control grid of the radio frequency amplifier 3. This connection may include a source 54 of grid bias voltage, which may be derived from any suitable source to thereby make the control grid bias independent of the self-bias. The cathode of the diode may be grounded through a self-bias resistor 56, which provides a "delay voltage." The term "delay voltage" refers to the threshold value of voltage at which the audio automatic, sensitivity control operates rather than the "time" at which it operates.

The operation of the foregoing circuit is essentially as follows: Signal currents, which are

induced in the loop and amplified by the radio frequency amplifier 3, are applied to the balanced modulators 7, 9 which are alternately keyed by potentials from the audio frequency generator 41. There are thus provided in the output circuit of the balanced modulator, modulated currents of side band frequency with a suppressed carrier frequency current. Because of the 90° phase shift in the radio frequency amplifier output circuit, the currents of side band frequency may be combined with carrier frequency currents from the non-directive antenna 15 so that the figure 8 response pattern of the loop, combined with the circular response pattern of the non-directive antenna, becomes a cardioid pattern. The output of the radio receiving device 19 will include currents of modulation frequency. The amplitude of these currents will vary and their phase reverse as a function of the loop orientation with respect to the wave front passing through the loop. These audio frequency currents of variable amplitude and reversible phase are applied to one of the field windings 33 of the two-phase motor. Currents of the same frequency but of fixed phase relation are applied to the other field winding 37. Therefore, depending upon the phase of the current derived from the received signals, the rotor 55 will be moved either clockwise or counter-clockwise. If no modulation currents are derived, i. e., when the loop is in the null position, no rotor movement will take place because only the reference phase current will be applied. Since the rotor is coupled to the loop by suitable means, indicated by the reference number 57, the loop will be rotated until a null position is reached. The loop position may be indicated by a pointer 58 and associated scale 60.

Neglecting for the moment the effect of audio frequency control of the sensitivity of the radio frequency amplifier 3, we have found that the ratio of the loop signal to the non-directional antenna signal is too small when the loop position approaches its null point, or too large when the loop is remote from its null position. The former condition may cause under-modulation and the latter over-modulation of the carrier current derived from the non-directive antenna. If the side band voltages in the output of the balanced modulator tubes greatly exceed the voltage from the non-directional antenna, the carrier from the antenna will be greatly over-modulated. Over-modulation reduces the fundamental components of the audio output. If the carrier is thus either under or over-modulated, the audio frequency output becomes greatly diminished and, since one of the phases of the audio frequency which operate the motor is thus diminished, the motor torque becomes very low. This condition is illustrated in Fig. 2.

To prevent the modulation components in the balanced modulators 7, 9 from over-modulating the carrier frequency currents in the non-directive antenna 15, we have arranged the automatic sensitivity control which operates as a function of the audio frequency output and thus can be designed to automatically increase or diminish the sensitivity of the radio frequency amplifier 3 to thereby maintain a substantially constant percentage modulation or constant audio frequency output. In this manner, over-modulation or under-modulation of the carrier frequency is prevented and thereby the audio frequency output currents of the receiving device

19 are maintained substantially constant so that the motor torque is substantially maintained until the null position is almost reached, as illustrated in Fig. 3.

5 Thus, the invention is described as a self-orienting direction finder in which the directive antenna is driven to a null position by means of a two-phase motor. The currents of two phases for the motor operation are derived from 10 a local alternating current source, which is used as a reference phase and by modulating the loop currents to derive output currents whose phases reverse as a function of loop orientation. In order that the modulated loop currents will not 15 over-modulate or under-modulate the carrier frequency current to thereby diminish the audio frequency output, an automatic sensitivity control is coupled to the audio output circuit of the receiver to thereby control the sensitivity of the 20 loop amplifier as a function of the audio frequency output. The operation of the automatic sensitivity control derived from the audio voltage may be delayed to thereby control the shape 25 of the control curve. It should be understood that the same invention may be used on a left-right indicator which may be substituted for the two-phase motor which orients the loop.

Likewise, the audio derived automatic sensitivity control voltage may be applied to change 30 the carrier voltage (derived from the non-directive antenna) so that the percentage modulation may be maintained substantially constant. If applied to regulate the carrier voltage from the non-directive antenna, we prefer to use an 35 additional radio frequency amplifier which will be controlled inversely as the control applied to the amplifier preceding the balanced modulator.

Such an arrangement is schematically illustrated in Fig. 4. The directive antenna 101 is connected through a radio frequency amplifier 103 to a balanced modulator 105. The balanced modulator is connected to an audio frequency generator 107, which is also connected through a phase shifter 109 to a reversible motor 111. The output of the balanced modulator 105 is applied to a radio receiver 113 which includes a demodulator. The radio receiver 113 has an input circuit which is connected through a radio frequency amplifier and phasing circuit 115 to a non-directive antenna 117. The radio receiver output is applied to an audio amplifier 119 and hence to a band pass filter 121. The output from the band pass filter is impressed on a second audio amplifier 123 and hence upon the reversible motor 111 to apply thereto the current of second phase. The motor 111 is coupled mechanically to the directional antenna 101 and to an indicator 125. The output of the band pass filter 121 is also impressed on an automatic sensitivity control 127 which is connected to the radio frequency amplifier 115 in the non-directive channel 117, 115, 113. The output of the second audio amplifier 123 is thus sustained in accordance with the previous description relating to Fig. 3. It is not necessary to describe in detail the elements which make up the circuit because the several elements previously described may be substituted for the corresponding elements of the block diagram.

70 We claim as our invention:

1. In a radio direction finder, the combination of a directive antenna, a non-directive antenna, an amplifier connected to said directive antenna, said amplifier including means for shifting the

phase of the amplified currents in a constant direction independently of their frequency, a modulation current source, a balanced modulator connected to said source and supplied with high frequency currents derived from said directive antenna for modulating said last mentioned derived currents to produce currents of side band frequency, a radio receiver, means for applying a carrier frequency current derived from said non-directive antenna and currents of side band frequency derived from said directive antenna to said receiver so that a demodulated current corresponding to said side band frequency may be derived from said receiver, means for rectifying said demodulated current to derive a controlling voltage, and means for applying said controlling voltage to said amplifier.

2. A radio direction finder including, in combination, a directive antenna, a non-directive antenna, radio frequency amplifier connected to said directive antenna, said amplifier including means for shifting the phase of the amplified currents in a constant direction independently of their frequency, a radio receiver, a balanced modulator connected to said radio frequency amplifier and supplied with high frequency currents derived from said directive antenna, a source of audio modulation current, means for applying said modulation current to said balanced modulator for modulating current derived from said directive antenna for producing current of side-band frequency, means coupling said non-directive antenna and said balanced modulator to said radio receiver, means for deriving an audio frequency output current from said receiver, said audio current varying in amplitude and reversing in phase as a function of the angular relation between said directive antenna and an approaching wave front, means for deriving a controlling voltage from said audio output current, and means for applying said controlling voltage to said radio frequency amplifier to maintain said audio frequency current substantially constant in amplitude for a signal received throughout the regions of the directive response of said directive antenna excepting the positions adjacent the null points of said directive antenna.

3. A radio direction finder including, in combination, a directive antenna, a non-directive antenna, a radio frequency amplifier connected to said directive antenna, said amplifier including means for shifting the phase of the amplified currents in a constant direction independently of their frequency, a radio receiver, a balanced modulator connected to said radio frequency amplifier and supplied with in phase radio frequency currents derived from said directive antenna, an audio frequency current source, means for applying currents from said source in out of phase relationship to said balanced modulator to modulate said radio frequency currents, means coupling said non-directive antenna and said balanced modulator to said radio receiver, means for deriving an audio frequency current from said receiver, said audio current varying in amplitude and reversing in phase as a function of the position of said directive antenna, means for deriving a controlling voltage from said audio frequency current, and means for applying said controlling voltage to said radio frequency amplifier to thereby maintain said audio frequency current substantially constant in amplitude for a signal received in all positions of said directive antenna excepting the positions adjacent the null points of said directive antenna.

4. A radio direction finder including, in combination, a directive antenna, a non-directive antenna, a radio frequency amplifier connected to said directive antenna, said amplifier including means for shifting the phase of the amplified currents in a constant direction independently of their frequency, a radio receiver, a balanced modulator connected to said radio frequency amplifier, means for applying an audio frequency modulation current to said balanced modulator, means coupling said non-directive antenna and said balanced modulator to said radio receiver, means for deriving an audio frequency current from said receiver, said audio current varying in amplitude and reversing in phase as a function of the position of said directive antenna, means for deriving a controlling voltage from said audio output current, and means for applying said controlling voltage to said radio frequency amplifier so that said audio frequency current is maintained substantially constant for a signal received in all positions of said directive antenna excepting the positions adjacent the null points of said directive antenna.
5. A radio direction finder including, in combination, a directive antenna, a non-directive antenna, a radio frequency amplifier connected to said directive antenna, said amplifier including means for shifting the phase of the amplified currents in a constant direction independently of their frequency, a radio receiver, a balanced modulator connected to said radio frequency amplifier, means for applying an audio frequency modulation current to said balanced modulator, means coupling said non-directive antenna and said balanced modulator to said radio receiver, means for deriving an audio frequency current from said receiver, said audio current varying in amplitude and reversing in phase as a function of the position of said directive antenna, means for deriving a controlling voltage from said audio output current, means for applying said controlling voltage to said radio frequency amplifier so that said audio frequency current is maintained substantially constant for a signal received in all positions of said directive antenna excepting the positions adjacent the null points of said directive antenna.
6. A radio direction finder including, in combination, a directive antenna, a non-directive antenna, a radio frequency amplifier connected to said directive antenna, said amplifier including means for shifting the phase of the amplified currents in a constant direction independently of their frequency, a radio receiver, a balanced modulator connected to said radio frequency amplifier, means for applying an audio frequency modulation current to said balanced modulator, means coupling said non-directive antenna and said balanced modulator to said radio receiver, means for deriving an audio frequency current from said receiver, said audio current varying in amplitude and reversing in phase as a function of the position of said directive antenna, means for deriving a controlling voltage from said audio output current, means for applying said controlling voltage to said radio frequency amplifier so that said audio frequency current is maintained substantially constant for a signal received in all positions of said directive antenna excepting the positions adjacent the null points of said directive antenna.
7. A radio direction finder including, in combination, a directive antenna, a non-directive antenna, a radio frequency amplifier connected to said directive antenna, said amplifier including means for shifting the phase of the amplified currents in a constant direction independently of their frequency, a radio receiver, a balanced modulator connected to said radio frequency amplifier and supplied with high frequency currents derived from said directive antenna, a source of audio modulation current, means for applying said modulation current to said balanced modulator for modulating current derived from said directive antenna for producing current of sideband frequency, means coupling said non-directive antenna and said balanced modulator to said radio receiver, means for deriving an audio frequency output current from said receiver, said audio current varying in amplitude and reversing in phase as a function of the angular relation between said directive antenna and an approaching wave front.

between said directive antenna and an approaching wave front, means for deriving a controlling voltage from said audio output current, means for applying said controlling voltage to said radio frequency amplifier to maintain said audio frequency current substantially constant in amplitude for a signal received throughout the regions of the directive response of said directive antenna excepting the positions adjacent the null points of said directive antenna, a reversible motor, means mechanically coupling said motor to said directive antenna, and means for applying said audio frequency current to said motor to control its operation and to orient said directive antenna as a function of the signals received thereon.

7. A radio direction finder including, in combination, a directive antenna, a non-directive antenna, a radio frequency amplifier connected to said directive antenna, said amplifier including means for shifting the phase of the amplified currents in a constant direction independently of their frequency, a radio receiver, a balanced modulator connected to said radio frequency amplifier and supplied with high frequency currents derived from said direction antenna, a source of audio modulation current, means for applying said modulation current to said balanced modulator for modulating current derived from said directive antenna for producing current of sideband frequency, means coupling said non-directive antenna and said balanced modulator to said radio receiver, means for deriving an audio frequency output current from said receiver, said audio current varying in amplitude and reversing in phase as a function of the angular relation between said directive antenna and an approaching wave front, means for deriving a controlling voltage from said audio output current, means for applying said controlling voltage to said radio frequency amplifier to maintain said audio frequency current substantially constant in amplitude for a signal received throughout the regions of the directive response of said directive antenna excepting the positions adjacent the null points of said directive antenna, a two-phase motor including field windings, a source of modulation frequency current, means for applying said modulation frequency current to said balanced modulator and to one of the field windings of said motor, and means for applying to the other of said field windings said derived audio frequency current, and means coupling said motor to said directive antenna so that said directive antenna is oriented as a function of said modulation frequency currents and said substantially constant audio frequency current.

8. In a direction finder including a motor for orienting a directional antenna, the method of indicating direction which comprises deriving a first carrier frequency current from waves whose wave fronts are to be indicated, deriving a second carrier current which varies in amplitude as a function of the disposition of said wave front, modulating said second carrier current, deriving currents of side band frequency and eliminating the carrier frequency of said modulator carrier, combining said first carrier and said side band frequency currents, demodulating said currents, deriving a controlling voltage from said demodulated currents, applying said controlling voltage to one of said carrier currents to maintain the amplitude of said demodulated currents substantially constant except when said second carrier currents are at their null condition, and indicating direction by applying said

modulating currents and said demodulated currents to said motor to orient said directional antenna.

9. In a direction finder including a directive and a non-directive antenna, a motor for orienting said directive antenna, and an indicator, the method of orienting an indicator to indicate the angular relation of a wave front and said directive antenna which comprises deriving a carrier frequency current from said non-directive antenna, deriving a second carrier frequency current which varies in amplitude and reverses in phase as a function of said angular relationship, applying modulation currents to said second carrier current, deriving side band frequency currents from said modulated carrier, eliminating currents of said second carrier frequency, combining said first carrier and said side band frequency currents, demodulating said combined currents, deriving a controlling voltage from said demodulated currents, applying said controlling voltage to one of said carrier currents to maintain substantially constant percentage of said side band currents with respect to said first carrier currents except in the region where said phase reverses, deriving forces from said modulation currents, deriving forces from said demodulation currents, and applying said forces to operate said motor to orient said directive antenna and said indicator.
10. In a direction finder including a directive and a non-directive antenna, and a motor for orienting said directive antenna, the method of orienting an indicator to indicate the angular relation of a wave front and said directive antenna which comprises deriving a carrier frequency current from said non-directive antenna, deriving a second carrier frequency current which varies in amplitude and reverses in phase as a function of said angular relationship, applying modulation currents to said second carrier current, deriving side band frequency currents from said modulated carrier, eliminating currents of said second carrier frequency, combining said first carrier and said side band frequency currents, demodulating said combined currents, deriving a controlling voltage from said demodulated currents, applying said controlling voltage to one of said carrier currents to maintain substantially constant percentage of said side band currents with respect to said first carrier currents except in the region where said phase reverses, deriving forces from said modulation currents, deriving forces from said demodulation currents, and applying said forces to operate said motor to orient said directive antenna and said indicator.
11. In a direction finder including a directive and a non-directive antenna and an orienting motor, the method of orienting said directive antenna to indicate the angular relation of a wave front and said directive antenna which comprises deriving a carrier frequency current from said non-directive antenna, deriving a second carrier frequency current which varies in amplitude and reverses in phase as a function of said angular relationship, amplifying said second carrier current, applying modulation currents to said amplified second carrier current, deriving side band frequency currents from said modulated carrier, eliminating currents of said second carrier frequency, combining said first carrier and said side band frequency currents, demodulating said combined currents, deriving a controlling voltage from said demodulated currents,

applying said controlling voltage to control said amplifying and to thereby maintain substantially constant percentage of said side band currents with respect to said first carrier currents except in the region where said phase reverses, applying said modulation currents and said demodulated currents to said motor to control the orientation of said directive antenna as a function of the angular relation between said directive antenna and said wave front.

12. A radio direction finder including, in combination, a directive antenna, a non-directive antenna, a radio frequency amplifier connected to one of said antennas, said amplifier including a phase changing circuit, a radio receiver, a balanced modulator connected to the other of said antennas and supplied with currents from said antenna, a source of audio current, means for applying said audio current to said balanced modulator to modulate said antenna currents, means coupling the output of said radio frequency amplifier and said balanced modulator to said radio receiver, means for deriving an audio frequency current from said receiver, said audio current varying in amplitude and reversing in phase as a function of the position of said directive antenna, means for deriving a controlling voltage from said audio frequency current, and means for applying said controlling voltage to said radio frequency amplifier to thereby maintain said audio frequency current substantially constant in all positions of said directive antenna excepting the positions adjacent the null points of said directive antenna.

13. A radio direction finder including, in combination, a directive antenna, a non-directive antenna, a radio frequency amplifier connected to said directive antenna, said amplifier including a phase changing circuit, a radio receiver, a balanced modulator connected to said radio frequency amplifier and supplied with high frequency currents from said directive antenna, a source of audio current, means for applying said audio current to said balanced modulator to modulate said antenna currents, means coupling said non-directive antenna and said balanced modulator to said radio receiver, means for deriving an audio frequency current from said receiver, said audio current varying in amplitude and reversing in phase as a function of the position of said directive antenna, means for deriving a controlling voltage from said audio frequency current, and means for applying said controlling

voltage to said radio frequency amplifier to thereby maintain said audio frequency current substantially constant in all positions of said directive antenna excepting the positions adjacent the null points of said directive antenna.

14. A radio direction finder including, in combination, a directive antenna, a non-directive antenna, a radio frequency amplifier connected to said non-directive antenna, said amplifier including a phase changing circuit, a balanced modulator connected to said directive antenna and supplied in phase high frequency currents therefrom, a source of audio frequency current, means for applying said audio frequency current in out of phase relation to said balanced modulator, means coupling the output of said amplifier and said balanced modulator to said radio receiver, means for deriving an audio frequency current varying in amplitude and reversing in phase as a function of the position of said directive antenna, means for deriving a controlling voltage from said audio frequency current, and means for applying said controlling voltage to said radio frequency amplifier to thereby maintain said audio frequency current substantially constant in all positions of said directive antenna excepting the positions adjacent the null points of said directive antenna.

15. A radio direction finder including, in combination, a directive antenna, a non-directive antenna, a radio frequency amplifier connected to one of said antennas and including a phase changing circuit, a second radio frequency amplifier connected to the other of said antennas, a radio receiver, a balanced modulator connected to the output of one of said radio frequency amplifiers, means coupling the output of the radio frequency amplifier which is not coupled to the balanced modulator and the output of said balanced modulator to said radio receiver, means for deriving an audio frequency current from said receiver, said audio frequency current varying in amplitude and reversing in phase as a function of the position of said directive antenna, means for deriving a controlling voltage from said audio frequency current, and means for applying said controlling voltage to either of said radio frequency amplifiers to thereby maintain said audio frequency current substantially constant in all but the null positions of said directive antenna.
